UNITED STATES PATENT OFFICE.

ARTHUR JOSEF ZIRGER, OF NEW YORK, N. Y.

HAIR-WAVING APPARATUS.

1,321,696.

Specification of Letters Patent. Patented Nov. 11, 1919.

Application filed February 19, 1919. Serial No. 277,942.

To all whom it may concern:

Be it known that I, ARTHUR JOSEF ZIRGER, a citizen of the United States, and a resident of the city of New York, borough of 5 Manhattan, in the county and State of New York, have invented a new and Improved Hair-Waving Apparatus, of which the following is a full, clear, and exact description.

The object of the invention is to provide 10 a new permanent hair waving apparatus arranged to insure the production of a permanent Marcel wave in a very simple manner and without danger of injury to the hair. Another object is to provide a simple apparatus 15 completely under the control of the operator to accomplish the desired result.

With these and other objects in view, the invention consists of certain novel features of construction, as hereinafter shown and 20 described and then specifically pointed out in the claims.

A practical embodiment of the invention is represented in the accompanying drawings forming a part of this specification, in 25 which similar characters of reference indicate corresponding parts in all the views.

Figure 1 is a perspective view of the improved apparatus for producing a permanent Marcel wave;

30 Fig. 2 is an enlarged perspective view of one of the heating and setting devices for a single strand of hair, parts being shown in section and parts being shown partly detached;

35 Fig. 3 is an enlarged sectional side elevation of the upper end of one of the heating and setting devices;

Fig. 4 is a sectional plan view of the same on the line 4-4 of Fig. 3; and

40 Fig. 5 is a diagrammatic view of the apparatus.

The hair to be permanently waved is divided into strands and each strand of hair 10 is wound exteriorly around a support 11 45 in the form of a tapering hollow core provided with perforations 12. The small end of the support 11 is provided with a grooved collar 13 adapted to be engaged by a tying string 14 for fastening the hair adjacent the 50 skin of the head in place as plainly indicated in Fig. 2. A moisture carrying envelop 15 incloses the strand of hair 10 wrapped around the support 11 and this envelop 15 is preferably formed of an inner wrapper 16 of flannel or a like material and an outer 55 wrapper 17 of paper. The envelop 15 fits

into the inner tubular metal wall 20 of a heater 21 having an outer wall 22 of asbestos or other suitable non-heat conducting material. The walls 20 and 22 are held in 60 spaced concentric relation by a bottom ring 23 and a head 24 of hard rubber or other suitable material.

Between the walls 20 and 22 are arranged a number of heating units 30, 31 and 32, 65 preferably of the electric type, and formed of resistance coils held spaced apart between concentric layers 33 of mica or similar material. The heating units 30, 31 and 32 are arranged for producing different degrees of 70 heat, for instance, the innermost heating unit 30 is designed for producing approximately 100° F., the heating unit 31 for producing 200° F., and the heating unit 32 for producing 300° F. The heating units 75 30, 31 and 32 are controlled by the operator in such a manner that either one may be used independently of the other, or any two or all three may be used simultaneously for producing in the aggregate 600° F. In 80 order to produce this result the terminals 35, 36 and 37 of the different units 30, 31 and 32 are adapted to be engaged singly or consecutively by a switch 40 in the form of a segmental band held on an arm 41 terminating in a hub 42 mounted to turn on a bearing 43 arranged on the head 24, as plainly shown in the drawings. The switch 40 is provided with a handle 44 under the control of the operator, and the switch 40 85 is connected by branch circuit wires 50 and line wires 51 connected with a source of electrical energy 52 and a rheostat 53, as indicated in Fig. 5. The switch wires 51 are provided with a switch 54 and the 90 branch circuit wires 50 are connected intermediate the switches 40 and 54 by wires 60 and 61 with electric heating units 62 and 63 in the form of resistance bars extending within the support 11 for the strand of hair. 100 The resistance bars 62, 63 are affixed to a cross bar 64 attached to the top of the heater 21. A switch 65 is arranged in the circuit wires 60 and 61 to permit of switching the current to the heating unit formed of the 105 resistance bars 62 and 63 whenever it is desired to heat the support 11. In practice the upper ends of the resistance bars 62 and 63 are attached to a head 70 from which lead the wires 60 and 61, and the head 70 is 110 held on one end of a cord or other suitable flexible connection slidingly engaging a

hook or other guideway 72 formed on a ring-shaped support 73 attached to a chandelier 74, as shown in Fig. 1. The flexible connection 71 is provided with a counterbalancing weight 75 for counterbalancing the hair waving apparatus with a view to relieve the strand of hair of undue strain. The branch wires 50 are arranged in cable form and each is supported by a socket 81 from a circular support 82 forming part of the chandelier 74. The wires 60 and 61 are similarly connected with the lower end of the chandelier thus permitting the use of a large number of hair waving devices on a 15 single overhead support in the form of a chandelier to allow of simultaneously waving all the strands of hair on the head of a person.

In using the apparatus the support 11 is 20 detached from the heater 21 and the strand of hair 10 is wound around the support and tied to the collar 13. Then the moisture soaked envelop 15 is placed in position to inclose the strand of hair and the support 11 25 with the strand of hair and the envelop 15 is pushed into the inner wall 20 of the heater 21. The operator now turns on the switch 65 to cause the heating of the air in the support 11 by the resistance bars 62 and 63. By 30 heating the support 11 the moisture in the envelop 15 is generated into vapor which thus steams and softens the strand of hair to retain the curled shape produced by winding the strand of hair around the support 11. Then the operator manipulates the switch 40 to first turn on the heating unit 30, then the heating unit 31 and then the heating unit 32 to gradually increase the heat of the heater 21, and finally to turn on the several units 30, 31 and 32 to produce a high 45 heat with a view to properly dry and set the previously softened strand of hair. When the setting of the hair is completed the heat is gradually turned off and the support 11 is removed from the heater 21 after which the envelop is removed from the strand of hair, the latter is untied and the support 11 is drawn out of the strand of hair which remains in curled shape on account of being 50 curled and set by the application of the moisture and heat as above explained. The strand of hair when subsequently combed out retains its wavy appearance.

It will be noticed that by the arrangement 55 described the operator in charge has complete control of the heating means to vary the temperature without danger of suddenly overheating the hair and thus injuring the same.

60 By making the support 11 tapering, the strand of hair at its thickest portion next to the scalp is wound on the small end of the support and as the strand grows thinner toward its end it winds on the gradually increasing portion of the support whereby the

final curl has a large opening at the thinner portion and hence the hair is not liable to kink and does not break on the final combing out. It will also be noticed that by this arrangement a more uniform wave is given 70 to the hair throughout the length thereof. It will also be noticed that the vapor readily passes through the apertures 12 in the support 11 into the latter and out of the same by way of the open upper end and 75 hence the heat is not liable to unduly heat the apex end of the support and thus injure the scalp.

Having thus described my invention, I claim as new and desire to secure by Letters 80 Patent:

1. A permanent hair waving apparatus, comprising a hair support around which a strand of hair is adapted to be wound, means for heating the said support, moisture 85 carrying means inclosing the support and the hair, and a heater inclosing the said moisture carrying means and having a plurality of heating units for heating the said moisture carrying means at different temperatures.

2. A permanent hair waving apparatus, comprising a hollow core around which a strand of hair is adapted to be wound, means for heating the said core interiorly, a moisture 95 carrying envelop surrounding the said core and the strand of hair, and a tubular heater surrounding the said envelop and having a plurality of heating units for heating the said envelop at different temperatures.

3. A permanent hair waving apparatus, comprising a hollow perforate core, heating means within the said core to heat a strand of hair wound around the core, a moisture 105 carrying envelop surrounding the strand of hair, and a tubular heater surrounding the said envelop and provided with a plurality of heating units for heating the envelop at different temperatures.

4. A permanent hair waving apparatus, comprising a hollow perforate core, heating means within the said core to heat a strand of hair wound around the core, a moisture carrying envelop surrounding the strand of hair, a tubular heater surrounding the said envelop and provided with a plurality of heating units for heating the envelop at different temperatures, and manually controlled means controlling the said heating 115 units to vary the temperature of the envelop.

5. A permanent hair waving apparatus, comprising a tapering hollow perforated core around which a strand of hair is adapted to be wound, the said core being provided at its small end with a collar to which the end of the strand of hair is fastened, an electric heating unit within the core, a moisture carrying envelop surrounding the core and strand of hair, a tubular 125

heater having spaced inner and outer concentric walls, the said envelop fitting into the inner wall, the said heater having a plurality of electric heating units arranged between the said inner and outer walls, the said heating units being of different strength, a source of electrical energy, and manually controlled means connecting the said source of electrical energy with the said heating units.

6. A permanent hair waving apparatus, comprising a tapering hollow perforated core around which a strand of hair is adapted to be wound, the said core being provided at its small end with a collar to which the end of the strand of hair is fas-

tened, an electric heating unit within the core, a moisture carrying envelop surrounding the core and strand of hair, a tubular heater having spaced inner and outer concentric walls, of which the inner wall is of metal and the outer wall is of a non-heat conducting material and forms a handle, the said envelop fitting into the inner wall, the said heater having a plurality of electric heating units arranged between the said inner and outer walls, the said heating units being of different strength, a source of electrical energy, and manually controlled means connecting the said source of electrical energy with the said heating units.

ARTHUR JOSEF ZIRGER.
